CLAIM
The ornamental design for a cartridge for electronic cigarette, as shown and described.

(**) **Term:** **15 Years**

DESCRIPTION

(21) **Appl. No.:** **29/925,207**

FIG. 1 is a front and top perspective view of a cartridge for electronic cigarette showing my new design according to an embodiment;

(22) **Filed:** **Jan. 23, 2024**

FIG. 2 is a front and bottom perspective view thereof;

(30) **Foreign Application Priority Data**

FIG. 3 is a front elevational view thereof;

Sep. 8, 2023 (CN) 202330585481.7

FIG. 4 is a rear elevational view thereof;

(51) **LOC (15) Cl.** **27-02**

FIG. 5 is a left side elevational view thereof;

(52) **U.S. Cl.**

FIG. 6 is a right side elevational view thereof;

USPC **D27/162**

FIG. 7 is a top plan view thereof;

(58) **Field of Classification Search**

FIG. 8 is a bottom plan view thereof;

USPC D27/162, 100, 101, 163–170, 172,
D27/174–176, 183, 185–194; D13/103,
D13/107; D23/360, 363, 366; D24/110,
D24/110.5

FIG. 9 is a front and top perspective view of a cartridge for electronic cigarette showing my new design according to another embodiment;

CPC A24F 40/00; A24F 40/05; A24F 40/10;
A24F 40/20; A24F 40/30; A24F 40/40;
A24F 40/42; A24F 40/90; A61M 15/06

FIG. 10 is a front and bottom perspective view thereof;

See application file for complete search history.

FIG. 11 is a front elevational view thereof;

(56) **References Cited**

FIG. 12 is a rear elevational view thereof;

U.S. PATENT DOCUMENTS

FIG. 13 is a left side elevational view thereof;

D751,978 S * 3/2016 Hong D13/103
D803,475 S * 11/2017 Scheiber D27/101
D825,837 S * 8/2018 Abroff D27/101

FIG. 14 is a right side elevational view thereof;

FIG. 15 is a top plan view thereof; and,

FIG. 16 is a bottom plan view thereof.

The broken lines in the drawings depict portions of the cartridge for electronic cigarette that form no part of the claimed design.

The dot-dash broken lines depict boundaries which form no part of the claimed design. The dashed broken lines and faded portions within dot-dash broken lines depict portions of the cartridge for electronic cigarette which form no part of the claimed design.
